URINALYSIS TEST UNIT CONTAINER

Thomas K. Hale, Glendale, Calif.

Application November 17, 1958, Serial No. 53,390

Term of patent 14 years

(Cl. D83—1)

Fig. 1 is a perspective view on a reduced scale of a urinalysis test unit container showing my new design in closed position.

Fig. 2 is a side elevation thereof.

Fig. 3 is an end elevation thereof.

Fig. 4 is a top plan view.

Fig. 5 is a side elevational view of the unit in open position.

Fig. 6 is a top plan view of Fig. 5.

Fig. 7 is an end elevational view taken from the right of Fig. 6.

I claim:

The ornamental design is a urinalysis test unit container, as shown.
